Attorney

UNITED STATES PATENT OFFICE.

CHARLES BLAMFIELD, OF BOSTON, MASSACHUSETTS.

TOY PISTOL.

1,260,306.

Specification of Letters Patent. Patented Mar. 26, 1918.

Application filed February 28, 1917. Serial No. 151,434.

To all whom it may concern:

Be it known that I, CHARLES BLAMFIELD, a subject of Great Britain, and a resident of the city of Boston, in the county of Suffolk and Commonwealth of Massachusetts, have invented certain new and useful Improvements in Toy Pistols, of which the following is a full, clear, and exact specification.

The object of this invention is the construction of a pistol whereby an ammunition strip can have its contained spots of explosive material, or "caps," successively exploded and the strip fed automatically to present the unexploded caps to the hammer.

Referring to the drawings forming part of this specification, Figure 1 is a side view of a toy pistol embodying my improvements. Fig. 2 is a side view of the same but with one of the two sections of the case removed. Fig. 3 is an end view showing the magazine cover open. Fig. 4 is a view in vertical transverse section on line X—X in Fig. 1, with the cover closed. Fig. 5 is a cross sectional view of the muzzle of the toy. Fig. 6 is an edge view of a section of ammunition strip. Fig. 7 is a perspective view of the principal member of the ammunition feeding means. Fig. 8 is a cross section of the hammer on a line close beside its actuating lug.

As shown in Fig. 3, the body or case of the pistol is made in two longitudinally separable members or sections, the section 1 being the one which contains the operative elements, and the section 2 being in effect a cover for suitably inclosing the elements. For the sake of clearness, I shall term the section 1 the main case, and will describe its construction and the parts carried therein before describing the remaining portion. Within the case 1 is the ammunition carrier or magazine 3 provided with a central stud 4 upon which to rotatably support a coiled strip of the ammunition 5. The outer end of this strip is led out toward the muzzle of the pistol close beneath its upper wall 6, access to this magazine being through an opening hereinafter described.

The means for feeding the ammunition strip to present a fresh explosive-dot to the hammer, comprises a trigger 7 pivotally supported at 9 and having a pin 10 at its inner end. Upon this pin is pivoted the

feeder proper 11 having its free end formed with the box-nose 12, a tension spring 13 attached to its hook 14 serving to retract it. When the trigger is pressed, as in the usual manner of firing a gun, the box-nose 12 incloses one of the explosive-dots 15 of the ammunition strip 5, while the feeder-lip 16 comes sharply against such dot and, as the feeder 11 is moved forward, the strip is carried along therewith. To render this engagement sure and positive, I have provided other means beside the tension of the spring 13 to press the box-nose tightly against the surface of the ammunition strip, the same means acting to effect another function.

Projecting from the box-nose 12 is a leaf 17 having an oblique flange 19 at its lower end, which is designed to meet and depress the hammer 20, and by the depression of 75 the latter against the action of a leaf spring 21, to give the above-referred to upward pressure of the box-nose 12 against the ammunition strip.

The hammer 20 is pivoted at 22, and by 80 the action of the spring 21 has its free end forced up against the ammunition strip. For tripping the hammer, it is formed with a lug 23 projecting upward into the path of the flange 19, and itself formed with an 85 oblique flange 24. When the tripper and feeder combined is advanced by the action of the trigger 7, the two oblique flanges come into engagement and the one slides over and depresses the other until they pass. 90 During such passage, the flange 19 forces the flange 24 downward to a distance sufficient for cocking the hammer, but the instant the flanges pass, the hammer freed from their engagement, flies upward against 95 the ammunition strip with force enough to explode the spot of explosive material thereat.

Now, as the trigger is released, the tension spring 13 retracts the feeder 11, but 100 the flange 24 being now in its uppermost position, the flange 19 engages its under surface and the box-nose 12 is withdrawn thereby from contact with the ammunition strip until it reaches substantially its normal position, when it rises into engagement with the strip. Inasmuch, however, as the flange 19 passes to a considerable distance beyond the normal position of the flange 24, as the latter is swung toward the muzzle of the pis- 110

tol during the depression of the hammer, this removal of the box-nose from the ammunition strip is but partial. To diminish the pressure between the box-nose and the strip during the entire return trip, and thereby prevent any back-feeding of the strip which might occur were there much pressure between the same, I provide a post 25 which projects from the case-member 2 10 and is hence shown in section in Fig. 2, and is adapted to be met by the spring 13 when the latter is elongated by the forward travel of the feeder. After being thus met by the spring, the latter is flexed thereby until its 15 pull is practically in a straight line with the pivot 22 and the box-nose 12, and is without power to press said nose either up or down. There being, therefore, no such pressure between the feeder and ammunition 20 strip, the latter is not affected thereby during the retraction of the feeder.

To further aid in securing the strip against any but a feeding action, I provide a detent 26 pivotally supported at 27 25 and formed with a bifurcated tail 28, 29, to the end of the latter of which the spring 13 is anchored, whereby the same spring acts both to retract the feeder, and to press the free end of the detent up against the ammunition strip. The tail-section 28 reaches outward from the case to provide an externally operative means for the removal of the detent from the top wall of the case during the introduction of the ammunition strip. By 30 35 pressing a finger rearward against the tail-section 28, the free end is swung a sufficient distance from the top-wall for the purpose specified.

The case section 2 is cut away along its 40 upper edge to form a suitable opening for the lateral introduction of the ammunition strip, and this opening is normally closed by a cover 30. This magazine cover is hinged to swing down to the position shown 45 in Fig. 3, and to be swung up to its closed position illustrated in Figs. 1 and 4. The hinge therefor is made as follows: In the lower edge of the wider portion 31 of the magazine cover is a hole 32 formed for the 50 purpose of providing a pivot member 33; and at the edge of the case-section 2 is a hooked finger 34 loosely gripping said pivot member, as shown in Fig. 4. A lug or abutment 35 projecting from the case 1 against the pivot member 33, serves so to press 55 against the latter as to slightly force the two case sections apart thereat, especially just before the cover reaches its closed position. The two case sections 1, 2 being 60 held together by screws 36, 37 located at considerable distances from this hinge, there is sufficient resilience in the metal composing the sections to allow them thus to be sprung apart, and by the resultant effect 65 upon the pivot member 33 to hold the cover

tightly closed, while permitting its being opened upon the application of a slight pressure against the ear 39 with which the cover is formed. As shown in Fig. 4, the pivot member 33 is shaped to press against the 70 finger 34 at a point above the level where the member 33 presses against the lug or shoulder 35, and thus to hold the cover closed.

The arrangement for hinging the other end of the cover comprises an eye formed 71 in the case section 2, and a finger projecting from the cover. The finger 40 is not only curved to suitably enter the eye 41, as shown in Fig. 5, but is given a slight bend at its end toward the pistol muzzle, as at 42, to 76 prevent its too easy withdrawal from the eye. To assemble the parts, the doubly bent finger is first hooked through the eye before the case section 2 has been applied to the case section 1, and then the other end of the 81 cover is swung down and into engagement with the finger 34. When the two case sections are then fastened together by the screws 36, 37, it is no longer possible to unship the cover from its hinging devices. 86

The extremity of the doubly hooked finger 40 serves still another function, namely, that of locking the hammer against accidental operation when the magazine cover is open. This is made clear in Fig. 5, where the said 91 finger is shown in the path of the hammer 20 and hence prevents the same from being actuated until after the cover is closed and the finger 40 is no longer in the way.

In use, this toy pistol has first to be loaded. 10 To do this, the magazine cover 30 is opened, and a coiled strip of the ammunition introduced, the coiled portion being mounted on the stud 4 and an uncoiled section thereof laid along beneath the top wall of 10 the pistol between the same and the detent and box-nose with the extreme end of the strip against the hammer. In doing this, the tail or auxiliary trigger 28 is slightly pressed against to move the detent away from the 11 said top-wall, the same action causing the box-nose also to be similarly moved, by the engagement of the end of the detent against the box-nose. The cover is then closed and the pistol is ready to be fired. 11

In firing the pistol, all that needs to be done is to pull the trigger 7, each pull feeding the strip to present a fresh spot of explosive to the hammer, the feeding occurring during the stroke of the hammer. This firing and feeding will continue so long as the trigger is intermittently pulled and released and until the ammunition strip is used up.

To contract the throat of the magazine for the better feeding of the ammunition 12 strip by means of a projection integral with the case section 1, would render the same practically incapable of casting or stamping, since the narrowness of the opening between the projection and top wall of the 12

case would render it liable to filling in if cast, and to other difficulties if stamped. I therefore form the throat by means of a projection 43 formed integral with the case 5 section 2, as indicated in Figs. 2 and 3.

The pin 44 shown in Fig. 2 serves both to confine the leaf spring 21 in place within the knee 45, and to act as a stop for limiting the rearward swing of the feeder 11 and the 10 upper end of the trigger 7. The post 25 above referred to similarly performs two functions, the first being the flexure of the spring 13 already described, and the second is to lock the leaf spring 21 against flying 15 out from its confining means 44, 45, or from working out into interference with the trigger. The other end of the leaf spring is similarly guided by a rib 46 projecting from the case section 2.

20 The oblique projection or ear 47 projecting from the case section 1 at the bend of the hammer shank, is designed to be engaged by the flange 19 at the extremity of the feeder's stroke and thereby to force the box-nose 12 so tightly against the ammunition strip as to absolutely assure against the explosive 25 spot therein taking fire when the hammer is setting off the adjacent one. Otherwise, when a single spot is exploded, the next and 30 each succeeding one would burn.

It should be noted that it is the rear of the box-nose 12 which does the feeding, its feeding lip 16 engaging the edge of the explosive spot or cap, and so positively causing 35 the strip to be advanced. Further, it is always a cap following the one to be fired, which is thus engaged by the box-nose, and is therefore inclosed therein and covered thereby.

40 If the ammunition strip available is not coiled but comes in a straight strip, it can be introduced longitudinally into the pistol through the breech aperture 49, without opening the ammunition cover 30.

45 The posts or projections 50, 51 and 52 formed integral with the case section 1, are for the better securing thereto of the case section 2.

The purpose of the leg 53 projecting from 50 the feeder 11 is to guide the latter and prevent its rotation on a longitudinal axis, the leg being in sliding contact with the upper part of the trigger 7 and the adjacent surface of the case section 2.

55 What I claim is:

1. A toy pistol comprising a case fitted to receive an ammunition strip, a hammer for exploding the strip section by section, and a feeder for the strip having a box nose for 60 both covering an unexploded section and for engaging and moving the strip, said box nose consisting of a member having a depression surrounded by a rim adapted to inclose on all sides between itself and the ammunition strip, each of the spots of explo-

sive material and thereby to prevent an explosion of an adjacent spot from affecting the spot inclosed.

2. A toy pistol comprising a case fitted to receive an ammunition strip, a hammer for 70 exploding the strip section by section, and a feeder for the strip having a box-nose having means forcing the box-nose into a temporarily tighter engagement with the strip at the termination of the feeder's movement 75 and during the firing action of the hammer, said box nose consisting of a member having a depression surrounded by a rim adapted to inclose on all sides between itself and the ammunition strip that spot of explosive material which is adjacent the one being exploded.

3. A toy pistol comprising a case fitted to receive an ammunition strip, a pivoted hammer having resilient means for percussively 85 actuating it, the hammer being formed with a thin lug and a flange rising from the extremity of the lug in a direction parallel with the pivotal axis of the hammer, and a feeder adapted to be forcibly moved substantially parallel with ammunition strip, 90 the feeder being adapted to engage said flange and both to trip the hammer and to be thereby pressed more strongly against the ammunition strip, the feeder being further adapted to return to its normal position 95 without interference with the hammer.

4. A toy pistol comprising a case fitted to receive an ammunition strip, a pivoted hammer having resilient means for its percussive actuation, the hammer being formed with a thin lug and a flange rising from the extremity of the lug in a direction parallel with the pivotal axis of the hammer, and a feeder adapted to be forcibly moved substantially parallel with the ammunition strip, 100 the feeder being provided with a flange substantially parallel with the first-named flange, said flanges being oblique to the line of advance of the feeder and adapted to mutually engage when the feeder is advancing and thereby to depress the hammer until they pass and the hammer swings into percussive engagement with the ammunition strip, and said flanges being also 110 adapted to pass without interference as the feeder returns to its normal position.

5. A toy pistol comprising a case fitted to receive an ammunition strip, a hammer for exploding the strip section by section, an 120 intermediately pivoted trigger, a feeder pivoted at one end to the upper part of the trigger, and a tension spring attached to the feeder to act both for its retraction and to press its feeder end into contact with the 125 strip.

6. A toy pistol comprising a case fitted to receive an ammunition strip, a hammer for exploding the strip section by section, an intermediately pivoted trigger, an elongated 130

feeder pivoted at its rear to the upper end of the trigger, a tension spring attached to the rear of the feeder at an acute angle with its line of direction, and a fixed post located 5 to meet and to flex the tension spring into substantial alinement with said line of direction during the latter part of the feeder's movement.

7. A toy pistol comprising a case fitted to 0 receive an ammunition strip, a hammer for exploding the strip section by section, a feeder for the ammunition strip, means for pressing the feeder and strip forward, a tension spring for retracting the feeder, a 500 detent pivotally supported at one end, and a tail rigid with the detent, said spring being attached to said tail and serving to press the free end of the detent against the ammunition strip.

8. A toy pistol comprising a case fitted to receive an ammunition strip, a hammer for exploding the strip section by section, a feeder for the ammunition strip, means for pressing the feeder and strip forward, a tension spring for retracting the feeder, a 500 detent pivotally supported at one end, a bifurcated tail rigid with the detent, said spring being attached to one of the bifurcations, the other bifurcation reaching out to the exterior of the case for enabling the detent to be pressed away from the ammunition strip, and the feeder and detent being disposed to cause the said pressing away of the detent to similarly move the feeder.

9. A toy pistol comprising a case having a magazine for receiving an ammunition strip, and a longitudinally extended opening,

means for exploding and feeding the ammunition strip, and a cover for said opening hinged to the case, the hinging means being 40 constructed to interfere with the operation of the hammer when the cover is open.

10. A toy pistol comprising a case having a magazine for receiving an ammunition strip, and a longitudinally extended opening, a pivoted hammer for exploding the ammunition strip, and a cover for said opening hinged to the case, a portion of the hinged means consisting of an eye near the path of the hammer, and a curved finger 50 projecting through said eye from the cover adapted to reach into the path of the hammer when the cover is open, but to avoid the same when the cover is closed.

11. A toy pistol comprising a two part case of slightly resilient material fastened together at spaced points, one of said parts being cut away and provided with a hinged cover for the cut-away portion, one of the hinging means consisting of a hooked finger 600 projecting from the edge of the cut-away portion, and a spindle-member carried by the cover in the control of the hooked finger, the spindle-member being irregular in cross section, and the other part of the case having a projection bearing against the spindle-member, the latter being shaped to slightly press apart the two parts of the case just prior to the entire closure of the cover, by 65 its engagement with the said projection.

In testimony that I claim the foregoing invention, I have hereunto set my hand this 26th day of February, 1917.

CHARLES BLAMFIELD.
